Attorney.

UNITED STATES PATENT OFFICE.

JOHN G. HEHR AND JOHN G. RILLING, OF SOUTH BEND, INDIANA.

IMPROVEMENT IN LAMP-EXTINGUISHERS.

Specification forming part of Letters Patent No. 173,465, dated February 15, 1876; application filed January 26, 1876.

To all whom it may concern:

Be it known that we, JOHN G. HEHR and JOHN G. RILLING, of South Bend, in the county of St. Joseph and State of Indiana, have invented a new and valuable Improvement in Lamp-Burner Extinguisher; and we do hereby declare that the following is a full, clear, and exact description of the construction and operation of the same, reference being had to the annexed drawings, making a part of this specification, and to the letters and figures of reference marked thereon.

Figure 1 of the drawing is a representation of a vertical elevation of my invention, partly in section. Fig. 2 is a top-plan view of the same. Fig. 3 is a plan view of the under side. Fig. 4 is a detached view of the several devices constituting my invention.

This invention is designed as an improvement upon the patent granted to J. G. Hehr, No. 169,263, October 26, 1875, wherein are employed weighted levers arranged in connection with hinged or pivoted hoods, so that the tipping or upsetting of the lamp will cause the weighted levers to bear against and throw either of the hoods over and cover the wick, thereby immediately extinguishing the flame. The object and purpose of the present invention, therefore, are to arrange the weighted levers in a manner that will economize space, and thereby take up less room, which will admit of the levers being more readily adapted to the various forms and styles of burners; also, in providing a means whereby the hoods may be operated independently of the weighted levers when found necessary to extinguish the flame, the construction and combination of the several parts being hereinafter described, and subsequently pointed out in the claims.

In the accompanying drawings, A is designed to represent the base, formed with an annular screw-threaded portion, *a*, and to which is connected, by suitable means, the frame B, having hinged thereto a cap, C. Passing through the base A is a wick-tube, *b*, to which is connected a wick-raiser, *c*. These parts, as above described, may be changed or modified, as found expedient, without departing from my invention, as I have merely shown this particular construction of parts

to best illustrate the arrangement of the devices constituting my invention.

Upon each side of the wick-tube *b* is a plate, *e*, held in position by a rod, *d*, such plates being formed with tongues *f*, passing down through an elongated slot in the frame B, which also assists in holding the plate in position. The plates *e* have turned-up lips *g*, through which the rods *d* pass, and upon which work the hoods *h*. The weighted levers, as represented at D, are constructed in the following manner: Plates *i* are formed with side flanges *j*, which are bent around a flat weight, *k*, to retain and hold it to the plate *i*, said plate being connected to the hood *h* by a tongue; *l*, formed on the plate, and passing up through a slot in the hood. The plates *i* are also formed with ears or flanges *m*, by which the same are pivoted to the flanges *n* of the plate *e* by short rods *o*. It will be seen that the weighted levers are suspended or pivoted in such a manner that the slightest tipping of the lamp will cause either of the two hoods to cover the wick and immediately extinguish the flame.

When it is desired to operate the hoods by other than automatic means, a curved lever, E, is employed, the same being connected to a plate, *p*, by tongues *q*, upon the under side of the frame B, the curved end of the lever E pressing against the under side of the weighted levers D; when pressure is brought upon the finger-piece *r* of the curved levers E, thereby throwing the hoods in position over the wick and extinguishing the flame.

Although we have described the weights *k* as being connected to the plates *i* by flanges *j*, we do not wish to be understood as limiting ourselves to this particular construction, as the weights may be secured to the plates by casting the metal around them, or forming the plate with several holes, by which a layer of metal may be held together upon each side of the plate during the process of molding the metal around it, as these means, together with various others, may be employed without departing from the principle of our invention.

Having now fully described the construction of our invention, what we claim, and desire to secure by Letters Patent, is—

1. In a lamp-extinguisher, the pivoted hoods *h*, in combination with the weighted levers *D* and levers *E*, substantially as and for the purpose set forth.

2. The combination, with pivoted hoods *h*, of the weighted levers *D*, consisting of the plates *i*, with flanges *j* and weights *k*, said plates or levers being connected to the hoods, *h*, by tongues *l*, passing through slots therein, substantially as and for the purpose specified.

In testimony that we claim the above we have hereunto subscribed our names in the presence of two witnesses.

JOHN G. HEHR.
JOHN G. RILLING.
